INVENTOR

John H. Nolan

UNITED STATES PATENT OFFICE.

JOHN H. NOLAN, OF BOSTON, MASS., ASSIGNOR, BY MESNE ASSIGNMENTS,
TO THE MAGNESO CALCITE FIRE-PROOF COMPANY, OF SAME PLACE.

SAFE.

SPECIFICATION forming part of Letters Patent No. 268,817, dated December 12, 1882.

Application filed February 23, 1882. (No model.)

To all whom it may concern:

Be it known that I, JOHN H. NOLAN, of Boston, in the county of Suffolk and State of Massachusetts, a citizen of the United States, have invented a certain new and useful Improvement in Safes, of which the following is a full, clear, and exact description, reference being had to the accompanying drawings, forming a part of this specification in explaining its nature, in which—

Figure 1 represents a front elevation of a safe containing my improvement; and Fig. 2 is a horizontal section, enlarged, of the safe-door.

15 The invention consists in providing the safe in a novel manner with a series of compartments, drawers, or boxes fastened to the inner side of the safe-door, by which the space between the front of the interior wood-work and 20 the door is utilized, and the interior of the safe made more available, and consequently more valuable.

25 In the drawings, A represents the safe, B the door, and C a frame-work, of wood or metal, fastened to the inner plate of the safe-door and having the compartments or spaces c for containing the drawers c'. These drawers may be of a length equal to the width of the frame; or they may be arranged, as shown in Fig. 2, 30 in two sets, one opening from one side of the door and the other from the opposite side. By this construction I am enabled to utilize a space in the safe which has heretofore not been of much service, and this is especially so in

connection with the safes made by the Fowler 35 Magneso-Calcite Fire-Proof Company, of Boston, which have a fire-proof lining, which enables the walls of the safe to be made much less thick than the walls of safes of the ordinary construction, thereby giving with a safe of the 40 same exterior dimensions much more room inside for the reception of books, papers, &c.

It will be observed that by arranging the drawers upon the safe-door, as described, a great convenience is effected, in that upon the 45 opening of the door the drawers are moved out from the interior of the safe to a position from which they can very readily be removed.

It has always been a great problem in safe-making to obtain the largest space and the 50 most convenient arrangement of the interior of the safe consistent with safety. By the means hereinbefore described I get, as I conceive, a perfect arrangement without jeopardizing in the least the safety of the contents of 55 the safe.

Having thus fully described my invention, I claim and desire to secure by Letters Patent of the United States—

In a fire-proof safe, the drawers c', located 60 between the door B and door-plate C, the said drawers arranged parallel with the inner face of the door, substantially as and for the purposes specified.

JOHN H. NOLAN.
